UNITED STATES PATENT OFFICE.

GUSTAF ABRAHAM LINDGREN, OF SODERFORS, SWEDEN.

MACHINE FOR MAKING WELDED TUBES.

Application filed July 1, 1921, Serial No. 481,941, and in Germany May 17, 1916. Renewed August 17, 1926.

My invention relates to the shaping and welding of tubes from strips of metal. In plants used for this purpose hitherto, the prepared strips of sheet metal are drawn 5 out of the heating furnace or oven by means of tongs, or by hooking them on uniformly moving chains. The strips are thereupon passed through drawing dies in which they are bent to a tube form and are pressed together at their two longitudinal edges and thus welded. Owing to the substantially uniform movement of the drawing chain, heavy shocks are produced especially on the entry of the tube blanks into the drawing 10 dies, resulting very often in damage and disarrangement of the plant, while also the strips are frequently torn. Very high costs for repairs and losses may thus be incurred. In addition to this, the hooking of the tongs 15 onto quickly running chains is rather difficult, so that interruptions may occur, resulting in overheating of the sheet metal strips.

These disadvantages are overcome by the present invention. This is attained by causing the drawing tongs to be moved, not as hitherto uniformly and continuously, but non-uniformly and in such a way that they grip the workpieces slowly and introduce them into the drawing die without shock, 20 and only after this do they gradually increase in speed up to that hitherto usual, or to a still greater working speed. This non-uniform movement is best attained by effecting the actuation of the drawing tongs 25 or their equivalent, or of the drawing head carrying these tongs, by means of a fluid, for example air or the like, which enters a cylinder behind a piston whose rod carries the drawing head. Moreover, with compressed air or the like, a resilient driving 30 medium is provided which takes up like a spring all shocks during the drawing, caused for example by unequal breadths of the strip.

45 In the drawings affixed to this specification and forming part thereof, a drawing plant embodying my invention is illustrated by way of example. In the drawings—

Fig. 1 is a plan view and

50 Fig. 2 a cross section, drawn to a larger scale.

Fig. 3 is a partial plan and

Fig. 4 is a rear view.

Beside a heating furnace a are arranged 55 on a bed b holders for the drawing dies c .

Through these dies drawing tongs f can pass, these tongs being hung in the open eyelets of drawing heads g , h . The drawing heads are securely attached to piston rods i , k whose pistons are slidable in long 60 cylinders l , m filled with fluid. The cylinders l , m are connected one with another at their rear ends through a pipe o ; at their front ends they are connected through pipes p , q comprising valves 1, 2 to the lower ends 65 of containers r , s , which are partly filled with liquid and are connected at their upper ends by pipes 3, 4 comprising a two-way cock y with a compressed air supply pipe z . The rods i , k are supported in their movements by rollers t disposed at intervals in the bed b . The bed is also formed with guide flanges u which are embraced by the drawing heads g , h (Fig. 2). The whole bed b can be oscillated about a pivot w 70 (Fig. 1).

The strips of sheet metal to be operated upon are heated in the furnace a and are bent together at the one end into a somewhat pointed form for the purpose of facilitating their introduction into the drawing dies c . The strip x lying in front of the drawing head h is gripped by the tongs f over which a drawing die is passed, the tongs are engaged in the eyelet of the drawing head 80 h and drawn slowly into the die holder. This movement is effected by introducing compressed air or the like above the liquid level in the container s , whereby the liquid is forced through the pipe q into the cylinder m . In consequence of this the piston moves slowly backwards with the rod k and the parts attached to it (drawing head, tongs and strip) so that the strip x is introduced 85 without shock and vibration into the drawing die, which latter has come to bear in the meantime against the die holder. When this has taken place the passage for the liquid is gradually made larger and larger, the consequence of which is that the piston 90 in cylinder m moves more and more quickly backwards, so that the actual drawing operation takes place at a comparatively high speed.

In its movement the piston forces out the 105 liquid behind it in the cylinder m , through the pipe o , into the cylinder l , causing the piston in this latter, the rod i and the drawing head g to be moved toward the furnace a . The liquid in front of the piston in the cylin- 110

2
 der *l* is thereby forced back again into the container *r*. The drawing head *g* thus comes into the position in which a further strip can be seized, while the strip held by the 5 tongs *f* has been drawn in the meantime completely through the drawing die and has thus been made into a tube. This tube is then freed from the drawing head *h*, and is carried by a transport band in the groove 10 *v* of the bed (Fig. 2) to a calibrating roller mill (not shown).

After the other tongs, upon which a drawing die has been thrust, have gripped a further strip, and have been drawn back into 15 the drawing head *g*, liquid is introduced from container *r* into the cylinder *l* in the same manner as above described for the cylinder *m*, whereby the piston in cylinder *l* is moved backwards with a gradually increasing speed, while the piston in the cylinder *m* is conducted in the opposite direction toward the furnace *a*. As the strips which previously lay in the furnace in line 20 with the two drawing heads have been removed, the whole bed *b* is now turned about its pivot *w* in such a manner that the tongs *f* come opposite the next strips in the furnace, and can grip the same.

There may be any number of cylinders 30 arranged on the bed *b* and the cylinders may be supplied with any other suitable pressure medium instead of liquid acted upon by compressed air.

Instead of the movement being effected by 35 means of pistons and piston rods any other method of driving can be used, provided that it is capable of being so controlled automatically or set in operation, that the movement of the drawing head can take place at a variable speed as described.

My invention is distinguished from previous devices of this kind in which two separate electric motor engines were used for the purpose of producing two different speeds in the different stages of the welding 45 operation by the fact that in my invention I provide means of effecting a gradual increase of power, and a cushioning action by

the use of a motor fluid and a cushion of liquid, and I am thereby enabled to perform 50 a much smoother operation of the working parts and a more efficient prevention of shocks and jarring and jerking movements than it is possible to produce by means of independently operating electric motors having 55 no provision whatever for the gradual swelling up of the power, which is a point of high importance for the prevention of the violent impact of the blanks against the forming devices and against the undue cropping of the edges of the tubes.

I wish it to be understood that I do not desire to be limited to the exact details of construction shown and described, for obvious modifications will occur to a person 60 skilled in the art.

I claim:

1. In a sheet metal tube drawing plant in combination, a die, means adapted to pass through said die for gripping a sheet metal strip, a cylinder and piston supplied with a liquid to the rear of said die for drawing said strip through said die and means for acting on the liquid in said cylinder with compressed air.

2. In a sheet metal tube drawing plant in combination, a pair of dies, means adapted to pass through each die for gripping a sheet metal strip, a cylinder and piston supplied with a fluid to the rear of each die and means for causing said pistons to alternate in their movements relatively to said dies and to move at varying speed.

3. In a sheet metal tube drawing plant in combination, a pair of dies, means adapted to pass through each die for gripping a sheet metal strip, a cylinder and piston supplied with a fluid to the rear of each die, means for causing said pistons to alternate in their movements relatively to said dies and to move at varying speed and means for acting on the fluid in said cylinders with compressed air.

In testimony whereof I affix my signature.

GUSTAF ABRAHAM LINDGREN.
